UNITED STATES PATENT OFFICE.

FRANK M. STEINER, OF MINNEAPOLIS, MINNESOTA, ASSIGNOR TO STEINER SALES COMPANY, OF SALT LAKE CITY, UTAH, A CORPORATION OF UTAH.

DESIGN FOR A TOWEL CABINET.

Application filed June 29, 1928. Serial No. 27,326. Term of patent 14 years

To all whom it may concern:

Be it known that I, FRANK M. STEINER, a citizen of the United States, residing at Minneapolis, in the county of Hennepin and State of Minnesota, have invented a new, original, and ornamental Design for Towel Cabinets, of which the following is a specification, reference being had to the accompanying drawing, forming part thereof.

The figure is a perspective view of a towel cabinet illustrating my new design.

I claim:

The ornamental design for a towel cabinet, as shown.

In witness whereof, I have hereunto set my hand this 27th day of June 1928.

FRANK M. STEINER.
